UNITED STATES PATENT OFFICE.

FRANK J. LAIRD, OF BUTTE, MONTANA.

DRILL-BIT DIE.

Application filed July 17, 1920. Serial No. 397,036.

To all whom it may concern:

Be it known that I, FRANK J. LAIRD, a citizen of the United States, residing at Butte, in the county of Silver Bow and State 5 of Montana, have invented certain new and useful Improvements in Drill-Bit Dies, of which the following is a specification.

The present invention relates to drill sharpeners and more particularly to a new 10 and useful improvement in clamping dies for use in Leyner, Sullivan, Waugh or other types of drill-sharpening machines.

It is the principal object of the invention to make provisions whereby a drill bit may 15 be finished in the clamping die instead of in an outside gauging block or forming die as has been the prevailing practice.

Another object is die mechanism whereby the amount of high carbon steel material 20 necessary for making bits for various types of drill steel is reduced to a small amount and whereby the split clamping die, which weighs about twenty to thirty-five pounds, 25 may be made of a poorer grade of steel, whether hardened or not.

Various other objects will appear from the description in connection with the accompanying drawings in which

Fig. 1 is a sectional view of a die embodying the invention;

Fig. 2 is an end view thereof;

Fig. 3 is an elevation of a modified form of split bushing, one of the halves only being shown; and

Fig. 4 is an end view of the complete bushing.

In the drawings 1 represents a split die which may be made of any suitable low priced material and 2 represents a split 40 bushing of high grade material, preferably high carbon tool steel.

The end 3 of the bushing 2 is of such proportions as to effectively withstand the heavy thrust upon it and is bearing against 45 a shoulder 4 in the die. The bushing also has a beveled shoulder 5 seated in a similarly shaped recess 6 in the die so that the bushing 2 is held in position in the die when the bottom and top parts are separated to 50 insert the steel to be sharpened or to remove the sharpened steel from it. The clamping face 8 of the bushing forms a continuation of the clamping face 7 of the die 1.

The principal feature with which this invention is identified is the double taper com-

prising the inner taper 9 and the outer smaller taper 10.

The significance of this double taper is as follows: The old practice of making double taper bits was to fashion the bit as a single 60 taper, using the dolly $\frac{1}{2}$ " or larger than the finished size of the drill and then to form the double taper by placing the bit in a separate gaging die and giving the required outside taper.

In the present instance, the double taper is made in a single operation. The stock is driven back into the die to form the double taper at the same time. The bit can in this manner be finished more accurately and perfectly than in the gage block in that the line of intersection between the outer and the inner taper will be placed accurately for every drill sharpened.

A different bushing will be required for 75 each size of bit. Since the bushing however, is of small size compared with the die, the expense is correspondingly reduced.

The device thus has the advantage to permit the renewing of a relatively small part 80 in place of the large expensive die, to make a drill bit to the required gage by changing bushings for each gage, to keep the steel in plain sight of the operator, to prevent overtravelling of dollies—reducing breakage 85 and wear of both dollies and springs, to make the gaging of bits mechanical instead of leaving it to the skill and judgment of the operator, to improve the steel sharpening standard and to get longer service from the 90 dies.

In Fig. 4 the outer taper of the bushing 12 has eccentric arcs 13 to make a double taper bit with clearance on the cutting corners.

In forming a double taper bit, it is essential 95 to have not only cutting faces but also reaming edges. These edges must have the same diameter as the face of the bit and also must have clearance. This is accomplished by arcs radiating from points equally spaced 100 off the center. Separate bushings may be used to place the clearance on the proper edge for right hand or left hand rotation.

I claim:

1. For use in drill-sharpening machines, 105 an axially split die having a removable split bushing constituting the forming element and means on the die and the bushing affording a self-centering interlocking engagement.

2. Arrangement according to claim 1 in which the die is made of low grade material and the bushing of high grade material.

3. For use in drill-sharpening machines, 5 a die the forming portion of which has a double taper, the outer one being less inclined toward the axis than the inner one.

4. Arrangement according to claim 3 in which the outer taper has eccentric surfaces affording clearance on the outer cutting 10 corners of the bit formed thereby.

In testimony whereof, I affix my signature.

FRANK J. LAIRD.
